UNITED STATES PATENT OFFICE.

WILHELM COERPER, OF BERLIN-ADLERSHOF, GERMANY.

BOOT-NAILING MACHINE.

Application filed September 30, 1924, Serial No. 740,812, and in Germany August 16, 1922.

This invention relates to a boot nailing machine. Machines of this type were fitted hitherto either with a horn or with a holder for an iron last. In the machines fitted with 5 a horn the conveying of the boot was effected by an awl stuck into the sole. The conveying can however not be effected in this manner when the machine is fitted with a last support as at the conveying of the comparatively heavy last support the awl breaks, 10 being adapted merely to convey the unloaded boot. The driving device for the horn is in machines of this type not capable of executing such a long stroke that it would be 15 possible to substitute without any modification a last holder for the horn.

The machines with last holder of known type are not adapted for the nailing by means of a horn as the feeding is in such 20 machines generally fitted with the fabric presser arranged for one side only so that when a horn would be substituted for the last holder the boot would tilt on said horn. There does consequently not exist a practical 25 boot nailing machine which is capable of working perfectly either with a horn or with a last holder.

The boot nailing machine according to my invention is designed to fill this gap.

30 The machine according to the invention can be used either with a last holder or with a horn. The feeder of the machine has a two-sided foot, known per se, and the carrier which supports either a last holder or a horn is adapted to execute a long stroke.

An arbor is preferably arranged so that it bears on the carrier for the last holder or the horn and engages with the hollow shaft of the last holder or the horn, a rod being 40 hingedly connected with said arbor, by the raising of which rod in a manner similar to a crowbar, the last holder or the horn is temporarily raised, the carrier being simultaneously secured in its position in order to press 45 during the working of the machine the work against the nose of the fastener inserting mechanism. The machine according to the invention is specially adapted to be used in boot-makers' workshops in which alternately new boots are made and repairs are executed. 50 The horn is best adapted for making new boots. This horn can however be used with advantage for repairing boots the welt of which is still undamaged and smooth and further for repairs of top boots as it is

difficult to accommodate the top on the last holder below the last. The nailing on lasts or the use of the last holder is necessary however when the bad state of the welt does not permit of a perfect feeding of the boot 60 on the horn. When machines of this type are to be used for nailing in two rows the feed foot is preferably controlled by a bush oscillatable around a bolt with the aid of a cam and adapted to be displaced on said bolt in axial direction by means of a capstan wheel operated by a cam. The carrier of the cam which operates the capstan wheel may be adjustable in the plane of the capstan wheel in order to permit passing from the 70 two-row nailing to the single-row nailing whereby the movement of the capstan wheel is stopped when passing from the two-row nailing to the single-row nailing.

It has further been found out that when 75 the feed foot, as has been hitherto usual in last holder machines, has an oscillating movement, namely a movement along a curved line, the selective use of a universal oscillatable last holder or of a horn movable 80 only in vertical direction was not possible for the nailing or that at least when the horn was being used, defects in the feeding of the shoe occurred. These inconveniences are avoided when, according to the invention, the feed foot of the machine executes at first a straight lined downward movement and then a straight lined movement in lateral direction. The feed foot is vertically moved downward by means of a ram 85 acting upon a sliding surface of the feed foot, whereupon it is moved in lateral direction by means of an oscillatable arm with which the feed foot is connected by a bolt engaging with a longitudinal slot. 90 The feed foot may be guided, with this object in view, by means of horizontal cross slots on the ram which is vertically guided.

In order that in the end position any play of the feed foot, and resulting therefrom, 100 an inaccurate nailing be avoided, a lever arm which effects the lateral movements of the feed foot may be fitted with a precisely worked curved face, which curved face holds the feed foot in its final position without 105 play in contact with the other guiding means, for instance the bolt.

In order that at a working of the machine 110 breakage of hammer or awl be avoided as far as possible, wherefrom troublesome in-

terruptions of the working would result, the hammer and awl, which with the object in view of becoming alternately operative, are mounted in an oscillatable guide piece can, 5 according to the invention, be guided at the upper end in the oscillatable frame which essentially is of a height corresponding to the length of hammer and awl, by means of the tool holder in longitudinal guides of said 10 oscillatable frame and at the lower end by engaging with a lower plate of said oscillatable frame so that the hammer and awl are consequently, in opposition to the commonly used arrangements, not guided only in 15 two places, but in three places. The double guiding in the commonly used machines is effected by the tool holder and the plunger situated directly above the tool. The third guiding is situated when the tool is penetrating into the work, approximately at the 20 centre of the tool, so that even in cases in which the work opposes considerable resistance to the penetration of the tool a breaking or bending of the tool need not be feared. 25 This arrangement ensures further a low building height. It is advantageous to arrange the last holder according to the invention in a plane perpendicular to the longitudinal axis of the last and inclined with regard to the shaft as with such arrangement the nails penetrate into the sole obliquely with regard to the edge of the sole and consequently have a more solid hold in the sole. 30 With this object in view the shaft which carries the last holder can be bent and directly below the last holder a ball-joint can be arranged adapted to be locked by means of a cap nut in order to permit of varying at will the angle of inclination of the last 35 holder.

An embodiment of the invention is shown, by way of example, on the accompanying drawings, in which:—

Fig. 1 is a side elevation of the machine, 45 partly in longitudinal section.

Fig. 2 is a front elevation of the machine.

Fig. 3 shows a side elevation, partly in section the horn mounted on the carrier.

Fig. 4 shows on enlarged scale the machine head in longitudinal section.

Fig. 18 is a side elevation of Fig. 17.

Fig. 19 is a section on line a—b of Fig. 17.

Referring to the drawings the machine consists of a column *a* with head *b* containing the driving gear for the nailing machine and of the work holder *c*. The rod 1 of the work holder *c* has threaded extension 2 at the lower end on which a nut 3 is adjustably mounted. This nut 3 is connected by springs 4 with the frame of the machine and by a link 5 with the pedal lever 6. The springs 4 press the rod 1 and consequently the last holder *d* or horn *f* mounted on said rod normally in upward direction so that the boot mounted on the last holder or on the horn is pressed against the machine head. The pedal lever 6 serves for pulling the boot away from the machine head with a long stroke in order to enable the adjusting 80 of the boot or any other manipulations. On the rod 1 either the last holder *d* or the horn *f* may be mounted. The last holder consists of the shaft 7 which is hollow at its lower end and bent so that its upper part is 85 inclined at an angle towards the lower part. On a stud 8 in the upper end of shaft 7 the extension piece 9 is mounted which has a bow-shaped cavity in its end designed to receive the bolt 10 of a plate 11 which carries the supports 12 for the last. The connection between the extension piece 9 and the plate 11 or the bolt 10 is ensured by means of a cap nut 13. In the ball joint formed in this manner the plate 11 and with the same the 90 supports 12 for the last may be adjusted at any desired angle with regard to the shaft 7 or to the rod 1.

On the bush 14 of the working table 15 which serves to guide the rod 1 an angle 110 lever 16 is pivotally mounted the shorter arm 17 of which has a screw 18 engaging with the rod 1. The end of this screw 18 is normally not in contact with the rod 1. If however the pull rod 19 hingedly connected with the end of the longer arm of lever 16 is moved upward by the action of the cam 20 the arm 17 is moved toward the rod 1 and clamps this rod in the bush 14. This clamping action takes place during the 120 working period proper of the machine, that is, during the working of awl and hammer. The rod 1 is securely fixed in its position by this clamping action so that a rigid abutment is produced instead of the elastic 125 counter pressure.

A lateral arm 19^a of the pull rod 19 serves to operate a lever 21 in the free end of which a bolt 22 is hingedly mounted. This bolt 22 is inserted between the upper face of rod 130

1 which is also ball-shaped and the bottom of the bore of the shaft 7. When, through the intermediary of the pull rod 19 or its arm 19^a, the lever is raised it acts like a 5 crowbar upon the shaft 7 in raising the same, whereby, the rod 1 being secured in its position, the pressure of the sole of the boot against the nose *g* is increased.

Instead of the last holder *d* the horn *f* 10 (Fig. 3) may be mounted on rod 1. The clamping lever 16 works also when the horn is being used.

The machine is driven either by power means or, as shown on the drawings, by 15 means of the pedal lever 23 which against the action of spring 24 acts upon the connecting rod 25 and through this connecting rod upon the fly wheel 26 which is keyed upon the driving shaft 27 of the driving 20 gear.

The driving shaft 27 carries at its front end the cams 28 (Figs. 4 and 5). These cams act upon abutments 29 which in Fig. 4 are shown in dash and dot lines and in 25 Fig. 5 in full lines. The abutments 29 of the hammer rod 30 are thus raised against the action of the spring 31. When the cams 28 continue to rotate the hammer rod descends under the action of spring 31. As 30 shown in Fig. 4 two pairs of cams are arranged, one in front of the hammer rod and the other behind said hammer rod. The rearward pair of cams serve to raise the hammer rod. The backs of the cams of the 35 front pair are of such shape that the downward movement takes place uniformly and at the desired speed. At the downward movement the abutment 29 remains permanently in contact with the front cams 28 so that no beating noise is produced.

As for raising the hammer rod 30 two cams 28 are arranged this hammer rod is raised and lowered twice at each revolution of the shaft. At one of these movements the 45 hammer rod is coupled with the hammer and at the other movement it is coupled with the awl through the intermediary of the mechanism which will be hereinafter described. The mechanism *h* (Figs. 4, 5 and 10) serves 50 for the coupling and uncoupling. On the axle 32 a frame 33 is oscillatably mounted. This frame comprises two guide rods 34 on which carriages 35 are guided so that they cannot rotate but move in axial direction. 55 These carriages 35 carry respectively the hammer 36 and the awl 37.

The frame 33 has teeth on its rear surface with which engages a rack 38. This rack 38 is moved to and fro by means of a lever 60 39 (Figs. 4 and 6) oscillatably mounted on the machine frame as the roller 41 of said lever engages with the curved groove of the cam disk 42 mounted on the driving shaft 27. By this reciprocating movement of the 65 rack 38 the frame is rocked. In the one end

position a nose 43, (Figs. 5-10) of the carriage 35 which carries the hammer 36 engages with an indentation 44 of the hammer rod 30. In the other end position of the frame 33 the nose 43 comes out of engagement with the indentation 44 and the nose 45 of the other carriage 35 for the awl 37 engages with an indentation 46 of the hammer rod 30. In the one end position of frame 33 the hammer and in the other end 70 position of the frame the awl is therefore coupled with the hammer rod. The hammer and awl are guided three fold during the entire working stroke, viz, at the upper end on the guide rods 34, at the middle in the lower 75 plate 47 of the frame 33 and at the lower end in the square hole of the nose *g*. The tools are therefore well protected against breaking and bending.

The peg-wood 47^a designed for the nailing 80 is conveyed by the milled wheel 48 (Figs. 5, 6 and 8) which presses the peg-wood 47^a against the guiding roller 49. The peg-wood bobbin is so mounted, that the direction of the strip entering the machine is 85 parallel to the plane in which the axes of counter-pressure roller 49 and guide roller 50 lie, so that the wood suffers no further bending in the machine. The milled wheel 48 is rigidly connected with a pinion 52 90 (Fig. 5) by means of an axle 51. A locking pawl 53 controlled by a spring 54 acts upon said pinion 52 and prevents the back rotation of the same. The rotation of the pinion 52 in forward direction is produced by a 95 pawl 55 which, against the action of a spring, is oscillatably mounted on a lever 56 and pressed by said spring which is not shown on the drawing, against the pinion 52. The lever 56 is oscillated by the cam 100 57 around the fulcrum 58 so that the pawl 55 rotates the pinion 52 and consequently the milled wheel 48 in forward direction. The peg-wood guide is closed at the front end by the lid composed of two parts 59 and 60 105 (Fig. 8). The two parts 59 and 60 of the lid are pivotably mounted on the bolt 61. The bolt 61 carries the guide roller 50. A screw 62 serves for securing the part 60 in 110 its position and a catch 63 serves for locking the part 59, said catch being pivotally mounted at 64 on the part 60 and carrying in its free end the set screw 65 by means of which the pressure exerted by the counter roller 49 on the peg-wood 47^a can be regulated. When a disturbance occurs in the 115 guiding of the peg wood it is merely necessary to oscillate the catch 63 back and to unscrew the screw 62 in order to render the box accessible which contains the peg wood. 120

The knife 66 which serves for cutting off the peg from the peg wood 47^a is hingedly connected with a lever 68 by means of a block 67 (Fig. 8). A reciprocating oscillating movement is communicated to this lever 125 130

68 through the intermediary of a rod 69 (Figs. 4, 6 and 12) the roller 70 of which engages with the curved groove 71 of the cam disk 42.

5 The work must be displaced at the single-row nailing in the direction of the row after each stroke of hammer and awl and at the two-row nailing once in the direction of the row and then transversely to this direction.

10 A feed foot 72 (Figs. 4, 7, 17) serves for controlling this movement of the work. The feed foot 72 has a lateral abutment 73 and two toothed pressure pieces 74 arranged at either side of the nose g (Figs. 4, 6, 7,
15 16-19).

The ram 75 for the feed foot 72 is guided by means of blocks 76 in vertical grooves 77 of the machine head 6 and further by means of bolts 79 engaging with slots 78. Springs 29 80 (Figs. 4 and 6) have the tendency to bring the ram into its upper position. The ram is moved in downward direction against the action of said springs by a cam 81 of the driving shaft 27. The lower end face 25 of the ram 75 bears on the face 82 of the feed foot 72.

The feed foot 72 or a flap 83 bent off at right angles is mounted movably in horizontal direction on the plate 84 which forms the end of the ram 75. The feed foot is guided by means of screws 86 engaging with longitudinal slots 85.

The flap 83 carries a screw 87 which engages with a longitudinal slot 88 of the arm 89 of a bush 91 rotatable around a bolt 90 screwed into the machine head. An upwardly directed arm 92 (Fig. 4) of bush 91 with which a spring 93 is connected cooperates with the cam 94 of the driving shaft 27 in such a manner that the arm 92, the bush 91 and the arm 89 of this bush are periodically swung out.

45 A bolt 95 is rigidly connected with the end of the bolt 90 and the capstan wheel 97 is rotatably mounted with its bush 96 on said bolt 95. The capstan wheel is periodically rotated by a cam 98 of the driving shaft 27.

50 An eccentric 99 connected with the bush 93 of the capstan wheel 97 acts at the rotation of the capstan wheel upon the face 100 of bush 91 whereby this bush is shifted in axial direction on the bolt 90. The feed foot 72 participates in this axial displacement. The axial displacement is utilized at the two-row nailing in order to pass periodically from one row of nails to the other row of nails.

60 The cam 98 is rotatably mounted on the driving shaft 27. At the side of this cam 98 a ring 101 is rigidly fixed on this shaft. A bush 102, arranged at the side of the ring 101, has pins 103 which traverse the ring 101 in axial direction. In the position 65 shown the pins penetrate into beres of the

cam 98 and couple the cam with the ring 101 and consequently with the driving shaft 27. In the side wall of the frame a lever 104 is pivotally mounted with the aid of a bolt 105 and carries eccentrically a stud 106 which traverses a slot of the wall of the casing and engages with an annular groove 107 of bush 102. In the position of the lever 104 shown in the drawings the cam 98 is coupled with the driving shaft 27. When however the lever 104 is oscillated in downward direction its stud 106 draws the bush 102 along so that the pins 103 disengage from the bores of the cam 98 so that this cam is stopped. The axial movement of the bush 91 ceases and the machine is adjusted for single-row nailing. The operation of the feed foot is as follows:—

By the cam 81 the ram 75 is at first pushed downward so that it descends vertically together with the feed foot 72. At this time the screw bolt 87 moves in the longitudinal slot 88 of arm 89 of the bush 91. As soon as the feed foot has arrived at its extreme lower position the cam 94 makes the arm 92 and the bush 91 and consequently the arm 89 of this bush swing sideward. The feed foot is thus laterally displaced on the plate 84 of ram 75 and the boot mounted on the horn or on the last holder is consequently fed for a distance between two nails.

The ram 75 rises again and with the same feed foot 72 so that the feed foot comes out of engagement with the boot. At two-row nailing the capstan wheel 97 begins now to operate. It shifts the bush 91 and with the same feed foot 72 in the longitudinal direction of the bolt 90 whereupon the above-described operation starts. In order to eliminate the idle run at and after the lateral movement and consequently inaccuracies in the adjusting of the feed foot 72 the arm 89 of the bush 91 has a projection 108 which is vaulted and accurately shaped in such a manner that it presses the feed foot 72 in its end position without play against the other guide elements, viz, against the screws 86. The return of the feed foot 72 into the initial position is effected through the action of the spring 109. 115

The amplitude of the oscillating movement of the bush 91 around the stud 90 may be adjusted by means of a screw 110 (Fig. 12). This screw limits the back movement of the arm 92 caused by the spring 93. The distance between two nails is altered by the amplitude of oscillation of the lever 92.

The awl and the hammer are at rest during the movements of the conveyor.

I claim:—

1. A boot nailing machine comprising a feed foot, a bolt, a bush for controlling said feed foot mounted for oscillation on said bolt, a cam movable around said bolt for operating said bush, a capstan wheel for op-

erating said cam, and cam means for operating said capstan wheel.

2. In a boot nailing machine of the type described, a mechanism for changing from two row to single row nailing, comprising means for shifting a shoe laterally during the nailing operation, a capstan wheel for operating said shifting means, a drive shaft, a cam for operating said capstan wheel loosely mounted on said drive shaft, and a clutch for clutching said cam to said drive shaft.

3. A boot nailing machine comprising in combination a vertically movable push rod, a feed foot mounted on said push rod by means of pins and horizontally extending slots, a rockable arm, and a connection between said arm and said feed foot consisting of a pin on said feed foot and a vertical slot on said arm.

4. A boot nailing machine comprising in combination a vertically movable push rod, a feed foot mounted on said push rod by means of pins and horizontally extending slots, a rockable arm, and a connection between said arm and said feed foot consisting of a pin on said feed foot and a vertical slot on said arm, and a precisely worked curved pressing face on said rockable arm designed to hold said feed foot in its end position against said guiding pins without play.

5. A boot nailing machine comprising a feed foot having a longitudinal slot, a ram acting on said feed foot for moving the same vertically downward, a bush, a cam for operating said bush, a lateral arm on said bush, and a pin on said arm engaging the slot in said feed foot for communicating straight line lateral movements to the feed foot.

6. A boot nailing machine of the type described comprising in combination a feed foot, a cam and push rod for depressing said feed foot, a plate at the lower end of said push rod having vertical slots, pins pro-

jecting through said slots for guiding the lower end of said push rod, and a flap on said feed foot projecting at right angles therefrom and having horizontal slots, and pins on said plate projecting through said horizontal slots.

7. A boot nailing machine of the type described comprising in combination with a feed foot having a longitudinal slot, a ram acting upon the upper face of said feed foot for moving the same vertically downward, a bush, a cam for operating said bush, a lateral rockable arm on said bush, a pin on said arm engaging with said longitudinal slot of the feed foot for communicating to said feed foot a straight line movement in a lateral direction, guide bolts for said feed foot, and a precisely worked curve-shaped pressing face on said rockable lateral arm designed to hold the feed foot in its end position without play against said bolts.

8. In a boot nailing machine of the type described a hammer, an awl, a rockable guide for the hammer and awl, comprising a rockable frame, two guide rods on said frame, a carriage movably guided on each guide rod, said hammer being mounted on one of said carriages, said awl being mounted on the other carriage, a hammer rod, means for rocking said frame to and fro to couple either the hammer or the awl carriage with said hammer rod, a lower plate on said frame in which the hammer and awl are guided, and a nose under the frame having a square hole for guiding said tools.

9. In a boot nailing machine of the type described, means for feeding peg wood comprising a counterpressure face for the peg wood, said counterpressure face being composed of two parts, a common pivot bolt for said two parts, and an adjustable catch for locking at least one of said parts in its position.

In testimony whereof I affix my signature.
WILHELM COERPER.
